UNITED STATES, PATENT OFFICE.

FRANK W. POHLMAN, OF SAN BERNARDINO, CALIFORNIA, ASSIGNOR OF ONE-FOURTH TO G. H. BUBLITZ, ONE-FOURTH TO E. B. REED, AND ONE-FOURTH TO A. O. CURRY, ALL OF SAN BERNARDINO, CALIFORNIA.

LOCK-NUT.

1,151,124.

Specification of Letters Patent. Patented Aug. 24, 1915.

Application filed January 28, 1915. Serial No. 4,879.

To all whom it may concern:

Be it known that I, FRANK W. POHLMAN, a citizen of the United States, residing at San Bernardino, in the county of San Bernardino and State of California, have invented new and useful Improvements in Lock-Nuts, of which the following is a specification.

The present invention relates to improvements in means for securing nuts and bolts against accidental removal, and the primary object of the invention is to provide a device of this character which shall be simple, cheap, easy to manufacture and which may be readily employed upon any ordinary bolt construction, and further which will perform the functions for which it is adapted with ease, accuracy and certainty.

With the above and other objects in view the improvement resides in the construction, combination and arrangement of parts set forth in the following specification and falling within the scope of the appended claim.

In the drawing: Figure 1 is a view of a nut and bolt constructed in accordance with the present invention, Fig. 2 is a sectional view approximately on the line 2—2 of Fig. 1, Fig. 3 is a perspective view of the locking element, and Fig. 4 is a sectional view 30 through the channel portion of the nut.

Referring now to the drawing in detail, 1 designates a bolt of any ordinary construction and 2 a nut therefor. The nut is provided with a passage 3 arranged tangentially thereof, the said passage communicating with one of the sides or faces of the nut and also communicating with the threaded bore of the nut. What may be termed the rear wall of the opening provided between the bore of the nut and the passage 3 is beveled toward the said passage to provide an inclined wall 4.

Arranged within the passage 3 and having one of its ends normally extending therethrough and projecting upon one of the sides of said nut is a locking member or dog 5. The dog 5 comprises an elongated member of a length to be snugly received within the passage, but the end 6 thereof is normally projected through the passage, through the medium of a spring 7 which exerts a compression between the rear wall of the passage and the inner end of the locking member or dog 5. The member 5 is

provided with a widened or thickened portion 8, which is normally arranged within the opening between the bore of the nut and the key or dog passage, the said enlargement having an arcuate or curved face which is provided with transverse teeth 9, and the end of the enlarged or thickened portion adjacent the angular wall or shoulder 4 is provided with an angular shoulder 10 which snugly engages with the angular wall 4, being normally retained in such position by the spring 7. When a wrench is applied upon the nut and contacts with the projecting end 6 of the locking member 5, the said locking member or dog will move first radially of the axis of the bolt opening, the same being directed by the shoulder 10 and wall 4, and the teeth 9 will be entirely forced out of the opening between the passage 3 and the bore of the nut, so that the nut may be readily unscrewed from the bolt. The widened or thickened portion 8, opposite its end provided with the inclined shoulder 10 is formed with a straight wall or shoulder 11, which normally contacts with a similar straight wall or shoulder 12 provided by the transverse wall of the said opening between the bore of the nut and the channel 3.

By reference to Fig. 2 of the drawing it will be noted that the passage 3, at what may be termed the lower wall thereof, is intersected by a longitudinally extending slot 50, the said slot, together with the passage, being sufficient to permit of the enlarged widened portion 8 being inserted therethrough. When the said widened portion 8 is brought adjacent the opening which communicates with the bore of the nut, the dog is rotated, so that one of the flat sides of said enlargement 8 will contact with the flat wall provided therefor in the passage, and the said passage as well as the slot 50 is then closed by a plug 60.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what I claim is:

In a nut lock, the combination with a bolt

and a nut therefor, said nut having a transverse passage which communicates with the bore of the nut and opens to one side of the nut, the said passage having its inner transverse wall at the juncture of the opening between the said passage and the bore of the nut inclined, a locking member adapted to be fully received within the passage, a spring within the passage and contacting between the end wall thereof and the inner end of the locking dog for forcing the second end of said dog through the passage and normally sustaining the same outward of the passage, said dog being formed with a

widened portion, the outer face of which being arcuate and being provided with transverse teeth which are normally projected in the bore of the nut, and the inner shoulder between the enlarged portion and the dog proper being inclined and resting upon the aforementioned inclined wall between the bore of the nut and the passage.

In testimony whereof I affix my signature in presence of two witnesses.

FRANK W. POHLMAN.
